(57) **CLAIM**

The ornamental design for a table base, as shown and described.

DESCRIPTION

FIG. 1 is a perspective view of a table base showing my new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof; and,

FIG. 7 is a perspective view to more fully illustrate the table base with a sample table top thereof.

The phantom lines in FIG. 7 are for illustrative purposes only to show a sample table top and form no part of the claimed design. The bottom of the table base is not part of the claimed design.
